DESIGN FOR A COMBINED HUB CAP AND WRENCH

John M. Fida, St. Paul, Minn.

Application September 15, 1948, Serial No. 148,592

Term of patent 7 years

(Cl. D90—12)

To all whom it may concern:

Be it known that I, John M. Fida, a citizen of the United States, residing at St. Paul, county of Ramsey, and State of Minnesota, have invented a new, original, and ornamental Design for a Combined Hub Cap and Wrench, of which the following is a specification, reference being had to the accompanying drawing, forming part thereof.

Figure 1 is a side elevational view of a combined hub cap and wrench, showing my new design;

Figure 2 is a top plan view of the same;

Figure 3 is a side elevational view showing the side thereof opposite that shown in Figure 1; and

Figure 4 is an end elevational view of the same.

I claim:

The ornamental design for a combined hub cap and wrench, as shown.

JOHN M. FIDA.
